The ornamental design for a portable telephone, as shown and described.

DESCRIPTION

FIG. 1 is a bottom, rear and right side perspective view of a portable telephone showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;
FIG. 7 is a left side elevational view thereof;
FIG. 8 is a bottom, rear and left side perspective view showing a condition, in which the display-side housing is opened at a substantially right angle to the operation-side housing;
FIG. 9 is a top, rear and right side perspective view showing a condition, in which the display-side housing is opened at a substantially right angle to the operation-side housing;
FIG. 10 is a front elevational view showing a condition, in which the display-side housing is opened at a substantially right angle to the operation-side housing;
FIG. 11 is a rear elevational view showing a condition, in which the display-side housing is opened at a substantially right angle to the operation-side housing;
FIG. 12 is a top plan view showing a condition, in which the display-side housing is opened at a substantially right angle to the operation-side housing;
FIG. 13 is a bottom plan view showing a condition, in which the display-side housing is opened at a substantially right angle to the operation-side housing;
FIG. 14 is a right side elevational view showing a condition, in which the display-side housing is opened at a substantially right angle to the operation-side housing;
FIG. 15 is a left side elevational view showing a condition, in which the display-side housing is opened at a substantially right angle to the operation-side housing;
FIG. 16 is a bottom, front and left side perspective view showing a condition, in which the display-side housing is opened;
FIG. 17 is a top, rear and left side perspective view showing a condition, in which the display-side housing is opened;
FIG. 18 is a front elevational view showing a condition, in which the display-side housing is opened;
FIG. 19 is a rear elevational view showing a condition, in which the display-side housing is opened;
FIG. 20 is a top plan view showing a condition, in which the display-side housing is opened;
FIG. 21 is a bottom plan view showing a condition, in which the display-side housing is opened;
FIG. 22 is a right side elevational view showing a condition, in which the display-side housing is opened;
FIG. 23 is a left side elevational view showing a condition, in which the display-side housing is opened;
FIG. 24 is a bottom, rear and right side perspective view of a portable telephone showing a second embodiment of our new design;
FIG. 25 is a front elevational view thereof;
FIG. 26 is a rear elevational view thereof;
FIG. 27 is a top plan view thereof;

FIG. 28 is a bottom plan view thereof;
FIG. 29 is a right side elevational view thereof;
FIG. 30 is a left side elevational view thereof;
FIG. 31 is a bottom, rear and left side perspective view showing a condition, in which the display-side housing is opened at a substantially right angle to the operation-side housing;
FIG. 32 is a top, rear and right side perspective view showing a condition, in which the display-side housing is opened at a substantially right angle to the operation-side housing;
FIG. 33 is a front elevational view showing a condition, in which the display-side housing is opened at a substantially right angle to the operation-side housing;
FIG. 34 is a rear elevational view showing a condition, in which the display-side housing is opened at a substantially right angle to the operation-side housing;
FIG. 35 is a top plan view showing a condition, in which the display-side housing is opened at a substantially right angle to the operation-side housing;
FIG. 36 is a bottom plan view showing a condition, in which the display-side housing is opened at a substantially right angle to the operation-side housing;
FIG. 37 is a right side elevational view showing a condition, in which the display-side housing is opened at a substantially right angle to the operation side housing;
FIG. 38 is a left side elevational view showing a condition, in which the display-side housing is opened at a substantially right angle to the operation-side housing;
FIG. 39 is a bottom, front and left side perspective view showing a condition, in which the display-side housing is opened;
FIG. 40 is a top, rear and left side perspective view showing a condition, in which the display-side housing is opened;
FIG. 41 is a front elevational view showing a condition, in which the display-side housing is opened;
FIG. 42 is a rear elevational view showing a condition, in which the display-side housing is opened;
FIG. 43 is a top plan view showing a condition, in which the display-side housing is opened;
FIG. 44 is a bottom plan view showing a condition, in which the display-side housing is opened;
FIG. 45 is a right side elevational view showing a condition, in which the display-side housing is opened; and,
FIG. 46 is a left side elevational view showing a condition, in which the display-side housing is opened.

The broken lines shown in the drawings are for illustrative purposes only and form no part of the claimed design.
